UNITED STATES PATENT OFFICE.

JAMES MILNOR HICKS, OF SUMMIT, NEW JERSEY, ASSIGNOR TO AUTO STOPPER COMPANY, OF NEW YORK, N. Y.

MEANS FOR SEALING VESSELS.

No. 895,461.

Specification of Letters Patent. Patented Aug. 11, 1908.

Application filed October 16, 1905. Serial No. 282,943. Renewed January 8, 1908. Serial No. 409,856.

To all whom it may concern:

Be it known that I, JAMES MILNOR HICKS, a citizen of the United States of America, residing at Summit, Union county, State of New Jersey, have invented certain new and useful Improvements in Means for Sealing Vessels, of which the following is a specification.

My invention relates to means for sealing vessels, and it consists in certain elements and combinations fully specified and claimed hereinafter.

In order that persons skilled in the art to which my invention appertains may understand, construct and use my invention, I will proceed to describe it referring to the accompanying drawings forming part of this specification in which

Figure 1 illustrates in elevation and part section a sealing cap applied to a vessel by stretching the pendent flange of smaller diameter than the bead upon the vessel neck surrounding its mouth, over said bead in accordance with my patent dated Feb. 21st, 1905, Number 783,038, but with the sealing stopper in the vessel mouth. Fig. 2 illustrates the same after it has been provided with my present invention. Fig. 3 illustrates the cap in elevation, before being applied to the vessel mouth as in Fig. 1, the same being of smaller internal diameter than the bead B upon the vessel neck. Fig. 4 illustrates the same after the indents F have been made in the cap shown in Figs. 1 and 3. Fig. 5 shows the cap of Fig. 4 in bottom view, the cap being removed.

A is the vessel neck. B is a bead upon the said neck surrounding the vessel mouth in the manner set out in the patent above referred to.

C is the pendent flange to the sealing cap.

D is the top flat surface of the cap. E is the stopper in the vessel mouth. F, Fig. 2 are indents formed in the pendent flange of the said cap beneath the bead B after the cap has been secured upon the vessel, as in Fig. 1, to firmly secure the cap upon the vessel against extraordinary pressure from within the vessel.

It will be readily seen that as in Fig. 1, the stopper is applied in the bottle mouth and the cap secured over it, the cap resting upon

the top of the walls of the vessel mouth, and forcing the stopper entirely within the vessel mouth so that the pressure from within 55 the vessel mouth forces the outer edge of the top of the stopper into the minute crack between the under surface of the top of the cap and the top surface of the walls of the vessel mouth, and the greater the force 60 against the base of the stopper the tighter will be the seal, in accordance with the principle set out in my Patent Number 746,332 issued Dec. 8th, 1903.

It is immaterial how the indents F are 65 produced as it is well known in the art.

It is important for the indents F to be made in the cap flange while the said flange is securely held circumferentially in order that the distorting of the metal of the flange 70 by forming the indents may not distort the remainder of the flange and tend to loosen the grip of the flange over and under the bead B.

No further description is needed to elucidate the invention contained herein.

Having now fully described my invention and the manner in which I have embodied it what I claim as new and as my invention and desire to secure by Letters Patent is 80

Means for sealing vessels, which consists in a vessel having a neck and a circumferential bead near its top; a sealing cap having a top surface and a flange pendent from said top surface of a diameter relative to the diameter of said circumferential bead upon the vessel neck, that the said cap flange when on the said vessel will closely and elastically contact with said bead and grip firmly beneath said bead, portions of said flange contacting under said bead, being turned under after the said cap has been pressed upon the vessel to its full limit, whereby a firm grip under said bead is obtained substantially as specified. 95

In testimony whereof, I have signed my name to this specification in the presence of two subscribing witnesses, this thirteenth day of October 1905.

JAMES MILNOR HICKS.
